TRACK CURTAIN HANGER.

Application filed October 10, 1925. Serial No. 61,770.

This invention relates to the class of track hangers for supporting curtains or the like.

The principal object of the present invention is to provide an improved means of the character mentioned for facilitating the suspension of a curtain or the like, and for permitting the curtain or the like to be readily moved.

The nature of the invention and its distinguishing features and advantages will appear when the following specification is read in conjunction with the accompanying drawing in which—

Figure 1 is a fragmentary perspective view of a portion of the track and one of the hangers of the present invention with a portion of a curtain shown attached to the hanger.

Fig. 2 is a transverse sectional view taken substantially on the line 2—2 of Fig. 1.

Fig. 3 is a sectional view taken substantially on the line 3—3 of Fig. 2.

Referring now more particularly to the several views of the drawing, it will be apparent that, the present invention contemplates the use of an element 10 with which will be associated a plurality of hangers such as the hanger 11. The element 10 is of tubular construction, the same preferably being cross sectionally square or of an angular formation, is divided longitudinally to provide spaced parallel tracks 12, 12, which are disposed in the same transverse plane. The hanger 11 includes a ball 13, and a ring member 14 which completely surrounds the ball, the ball being revolvably retained by said ring member. The ring member 14 is made from a single piece of material, cross sectionally arcuate to conform to the perimeter of the ball, and endless, or ends of a piece of material joined by the use of solder, or in any other suitable manner as at 15.

The hanger 11 also includes attaching means 16 which is carried by the ring member 14. In the present instance the attaching means 16 is in the nature of a loop or eye swivelled at 17 to the ring member 14. The loop or eye is adapted to accommodate a loop or hook such as the one 18 carried by a curtain 19 for effecting the suspension of the curtain. In practice, in which a number of hangers 11 will be used, the ball 13 of each hanger will be inside of the element 10, and will be supported by the tracks 12, 12, in revolving contact therewith. It is to be noted that the ball contacts with the upper side edges respectively of the tracks 12, 12, and the contact between the ball 13 and the tracks is such that the least possible resistance exists. It is to be noted that the opposite side portions of the ring member 14 prevent the disassociation of the ball 13 and ring member 14. Therefore, the ball 13 will be permitted to revolve freely without the possibility of being hindered as the hanger in its entirety is being moved by a force applied to the ring member 14 through the loop or hook 18 and the attaching means 16. It is further to be noted that the ring member 14 may move relatively to the ball 13 both circumferentially and laterally, thus effectually meeting all the exigent pulling forces applied thereto to permit the free and easy movement of the curtain.

What we claim is—

A track curtain hanger comprising a ball, a ring member completely surrounding said ball, said ring member being cross sectionally arcuate, the ball being revolvably retained by the opposite side portions of said ring member, and curtain attaching means carried by said ring member.

COURTENAY P. DAY.
